UNITED STATES PATENT OFFICE.

JOHN GRICAR, OF LOWELL, ARIZONA.

COAL-MINING MACHINE.

1,278,333.

Specification of Letters Patent. Patented Sept. 10, 1918.

Application filed January 25, 1917. Serial No. 144,518.

To all whom it may concern:

Be it known that I, JOHN GRICAR, a subject of the Emperor of Austria, residing at Lowell, in the county of Cochise and State 5 of Arizona, have invented certain new and useful Improvements in Coal-Mining Machines, of which the following is a specification.

This invention relates to new and useful 10 improvements in coal mining machines.

The primary object of the invention is the provision of a mining machine for coal, after the nature of the short-wall machine, the same being adapted for manual opera- 15

A further object of the device is the provision of a hand operated coal mining machine having an adjustable anchoring means whereby the cutting members may be fed 20 into the work to a limited extent without shifting the anchoring means.

In the drawing forming a part of this application and in which like-reference characters refer to corresponding parts 25 throughout the several views:

Figure 1 is a side elevation of the device.

Fig. 2 is a horizontal sectional view thereof.

Fig. 3 is a view partly in elevation and 30 partly in section upon line III—III of Fig. 1.

Fig. 4 is a longitudinal sectional view taken upon line IV—IV of Fig. 2.

Fig. 5 is a perspective view of one of the 35 side brackets of the anchoring member, and

Fig. 6 is a perspective view of one of the cutting members detached.

Referring more in detail to the drawing the device broadly consists of an oval-shaped frame 10 of channel-bar formation 40 having an upright inverted substantially U-shaped arch or anchoring member 11 centrally positioned therein adapted to adjustably engage the top and bottom of the mine 45 12 and 13, respectively, the said frame adapted for carrying manually operable cutters 14, and being longitudinally shiftably arranged upon the said anchoring member 11.

The anchoring member for the device 50 comprises oppositely positioned brackets 15 and 16 of similar formation arranged inwardly of the frame 10 with outwardly pro-

jecting flanges 17 within which the frame 10 is longitudinally slidably arranged in 55 horizontal position. The inner sides of the brackets 15 and 16 are provided with parallel vertical inclosing flanges 18 within which the parallel side beams 19 of the anchoring member 11 are seated and secured and 60 whereby the anchoring member is arranged perpendicularly with respect to the frame 10. A horizontal bottom beam 20 connects the brackets 15 and 16 together, the same assisting the enlarged feet 21 of the brackets 65 15 and 16 in forming a base upon which the anchoring member 11 may seat upon the mine bottom 13, affording a stable mounting means for the frame 10 of the machine, it being understood that an adjustable point 70 22 is threaded upon the holding member 23 at the top of the anchoring member 11 for forcible engagement with the top 12 of the mine whereby the member 11 is temporarily fixedly positioned at a desirable 75 point within the mine. A locking screw 24 is carried by the point 22 for maintaining the same in its adjusted position upon the member 23. Calks 17' are carried by the feet 17 for engagement with the bottom 80 of the mine. The anchoring member 11 and brackets 15 and 16 are readily separated from the frame 10 to facilitate transportation.

An operating shaft 25 is transversely 85 journaled upon the anchoring member 11, being provided with a plurality of turn cranks as illustrated at 26 in Fig. 1 and by dotted lines in Fig. 3 of the drawings. Stub-shafts 27 are journaled within angular arms 28 at the outer sides of the brackets 15 and 16 upon which gears 29 are secured in constant mesh with toothed racks 30 formed at opposite marginal points on the upper face of the frame 10. Sprocket chains 31 connect the shaft 25 with a sprocket 25' upon a sleeve 27' of the bracket 28 by running over a sprocket member 33 journaled on the shaft 25. The stub-shafts 27 are connected to the sleeves 27' by means of 90 gear wheels 32—32' mounted upon the said stub-shafts and sleeves. A clutch member 34 is arranged for each of the sprocket members 33, the same being splined upon the shaft 25 and adapted to be moved in and 95 out of clutching engagement with the 100 105

sprocket members by means of shift levers 35. It will be understood that by turning either or both of the cranks 26, when the clutch members 34 are in mesh with the sprocket members 33, as normally maintained by the springs 33' on the shaft 25, the stub-shafts 27 will be turned for feeding the frame 10 in the desired direction longitudinally upon the brackets 15 and 16, 10 simultaneously with the operation of said cutters 14 by the means hereinafter described.

A power chain 36 is arranged within the outwardly opened channel 37 of the frame 10 being mounted upon anti-friction rollers 38 carried within the frame and projecting outwardly through slots 39, the cutting member 14 being removably secured and suitably spaced apart upon the chain 36 by 20 bolts 40, the said members 14 being fitted for free sliding movement within the channel 37 of the frame. The cutting teeth 41 of the members 14 have sharpened outer edges 42 projecting from the frame 10 25 adapted for engaging the side of the mine and cutting the coal during the operative movement of the chain 36 in the direction indicated by an arrow in Fig. 2 of the drawings. Clearing teeth 14' are alternately arranged upon the chain 36 intermediate the teeth 14 for clearing away the cuttings, while differently formed teeth may be employed if desired.

A shaft or axle 44 is journaled in the bracket 16 between an extension 45 carried thereby and the adjacent foot 21, a sprocket wheel 46 being carried by the said axle in constant operative engagement with the power-chain 36 through a longitudinal slide 40 slot 47 of the frame 10, while a transverse shaft 48 is journaled between the extension 45 and the arm 49 of the opposite bracket 15. Beveled pinions 50 and 51 are carried by the shafts 48 and 44, respectively, being 45 in constant mesh with each other while the shaft 48 is operatively connected with the shaft 25 by means of a sprocket chain 52 passing over sprockets 53 arranged upon the said shafts. The bottom flange 37' of the 50 frame 10 has a plurality of openings 10' therethrough to allow the cuttings to drop beneath the frame, preventing the teeth from clogging.

The complete operation of the device will 55 be apparent from this detailed description thereof, the anchoring of the machine at the desired point within the mine having been already described. With the frame 10 arranged adjacent the wall of the mine, where- 60 by the cutting blades 42 will engage the coal, the cranks 26 are turned for revolving the sprocket wheel 46 thereby operatively moving the chain 36 and forcing the blades 42 into engagement with the work, while 65 simultaneously therewith the stub-shafts 27

are turned for feeding the frame 10 toward the wall being operated upon. The levers 35 may be operated to release the clutches whenever it is desired to operate the cutter chain 36 without feeding the frame 10 longitudinally.

It will be noted that a clutch connection is provided between the chain 52 and the shaft 25, the same consisting of a clutch member 10^a slidably splined upon the shaft 25 and adapted for clutching engagement with the sprocket member 11^a which is journaled upon the shaft 25 and over which the chain 52 runs, operating lever 12^a being provided for the said clutch. It will be understood that by releasing the clutch member 10^a the shaft 25 may be turned for feeding the frame 10 longitudinally withdrawing the teeth 14 from the work without operating the chain 36. By the arrangement herein described, the shaft 25 may be turned without operating either of the chains 31 and 52 or all simultaneously as found desirable, while the frame 10 or the chain 36 may be separately operated.

What I claim as new is:—

1. A coal mining machine including a pair of spaced oppositely positioned supporting brackets each having a pair of spaced horizontal outwardly positioned guide flanges 95 and a vertical inwardly positioned socket, a jack including an upright arch member having its ends removably received within the sockets of said brackets and adapted to connect the latter, a substantially oval horizontal channel frame longitudinally slidably guided and supported by said brackets between the horizontal flanges thereof, an endless coal cutter chain arranged in the channel of said frame, and means associated with 100 said brackets and said arch member to shift said frame and to operate said cutter chain.

2. A coal mining machine including a jack having an inverted substantially U-shaped upright member, a pair of spaced oppositely positioned brackets removably attached to the lower ends of the legs of said member and having base supporting feet, a horizontal substantially oval channel frame arranged outwardly of and longitudinally 115 shiftably guided and supported by said brackets, an endless coal cutter chain, operatively arranged in the channel of said frame, and means associated with said brackets and said upright member to operate said cutter 120 chain and to shift said frame.

3. A coal mining machine including a pair of spaced oppositely positioned brackets, each having a pair of horizontal outwardly positioned spaced flanges and a vertical 125 inner socket, a jack including an inverted substantially U-shaped upright member having the lower ends of its legs removably received within said sockets, a horizontal substantially oval channel frame longitudi- 130

nally shiftably guided and supported by said brackets between said horizontal flanges thereof, an endless coal cutter chain arranged in the channel of said frame, a trans-
verse power shaft carried by the legs of said upright member, toothed racks upon the upper flange of said frame, gears in con-

stant mesh with said racks and having operative connections with said power shaft, and operative connections between said power 10 shaft and the cutter chain.

In testimony whereof I affix my signature.

JOHN GRICAR.
